UNITED STATES PATENT OFFICE.

MYRELLE FRIEDMAN, OF NEW YORK, N. Y.

GARTER.

Application filed May 22, 1924. Serial No. 715,041.

This invention relates to women's garters and more especially is designed to provide a garter adapted for use in connection with women's rolled stockings, that is, for women's full length stockings, the ends of which are rolled and worn below the knees. In this position the upper portion of the stocking is lowered and rolled into a thickened circular band, instead of being worn in the customary manner. One of the objects of my invention is to provide a garter which will be a separate and complete article of manufacture having two bands of elastic provided with an intermediate shirred body portion, and which can be applied to the rolled portion of a stocking so that one of the bands of elastic can be located above the roll of the stocking and the other can be located below the roll of the stocking. My invention has no relation to garter devices forming an integral part of stockings, and which cannot therefore be applied to the roll of a stocking in the manner above mentioned.

Further objects of the invention will be apparent from the drawing in which—

Fig. 1 is a perspective view showing the manner in which my improved garter is worn.

Fig. 2 is a perspective view partly in section showing the garter in place.

Fig. 3 is a perspective view of the garter alone.

Fig. 4 is a sectional elevation.

Fig. 5 is a sectional view.

In this particular embodiment of my improved garter, the same is constructed of two separate and distinct narrow and continuous bands of elastic A and A' which are positioned at the top and bottom of the garter.

The body of the garter is made of silk or other suitable textile material, the edges of the silk being sewn over to form hems or into the elastic bands A and A' in the ordinary manner. The elastic bands A and A' are stretched with respect to the fabric B constituting the body of the garter as in the construction of ordinary garters, so that when the bands A and A' contract to normal, the body of the garter is contracted

into a series of ornamental shirrings or ruffles shown more clearly in Fig. 3 of the drawing. The effect of having the bands of elastic in this particular embodiment at the edges of the garter only, with no elastic in the middle, is to provide a garter which will be readily bendable in the middle forming a

pocket for holding the rolled top of the rolled stocking as well as concealing the roll. A garter made in this fashion will conform much better to the lines of the stocking and of the leg where rolled stockings are worn.

As shown in Fig. 5, when the garter is worn, the upper band of elastic A is located above the rolled portion of the stocking, and the lower band A' is located substantially below the rolled portion of the stocking and the relatively non-elastic fabric body portion of the garter is laterally extended to enclose the roll or rolled portion of the stocking. Hence, as can be clearly seen in Fig. 5, the width of the garter is slightly greater than the width of the roll or rolled portion of the stocking, so that the body portion B acts as a pocket to snugly enclose the roll of the stocking. Since the body of the garter has ruffles or gathers formed therein, it is freely extensible with respect to the bands of elastic so that it can enclose the roll R of the stocking without producing an uncomfortable binding effect when the bands of elastic are in the position shown in Fig. 5.

The same object as explained in this particular embodiment may be attained in a garter where the body is also made either of elastic material or even of sheet rubber and having a greater tension at the upper and lower edges of the garter than in the middle, so that the central portion of the garter is under less tension than the upper and lower edges. For instance, a garter may be made where the body of the same is of elastic webbing, but in this case the body should be under less tension than the edges of the garter.

Where the body of the garter is made for instance, of sheet rubber for bathing purposes, then the edges of the garter may also be made of rubber, but care should be taken that in this case also, such edges should have a greater tension than the middle portion of the garter. This could be accomplished by having the garter provided with thickened edges, for example. It is essential that the tension on the upper and lower edges of the garter be greater in order that a loose pocket be formed in the center of the garter.

Having thus fully described my invention, what I claim is:

As a complete article of manufacture, a garter having spaced independent bands of elastic connected to an intermediate body portion made of material less elastic than
